UNITED STATES PATENT OFFICE.

JAMES T. FIELDS, OF MASON CITY, ILLINOIS.

WHEEL-CLAMP.

1,187,056.

Specification of Letters Patent. Patented June 13, 1916.

Application filed March 18, 1916. Serial No. 85,157.

To all whom it may concern:

Be it known that I, JAMES T. FIELDS, a citizen of the United States, residing at Mason City, in the county of Mason and State of Illinois, have invented certain new and useful Improvements in Wheel-Clamps, of which the following is a specification, reference being had to the accompanying drawings.

10 This invention relates to an improved wheel clamp and has for its primary object to provide a simple and effective device for positively clamping the car wheels to the track rails when the journal box is raised or jacked up in order to insert a new brass, or for other necessary operations.

It is another and more particular object of the invention to provide a device for the above purpose embodying a clamping member having angularly projecting lips formed on its opposite ends for engagement with the car wheel flange and the outer side of the rail head respectively, and improved means for adjustably mounting a bolt shank in said member, said bolt shank having a hook formed on one end for engagement over the inner side of the rail head and an adjusting nut threaded upon its other end.

It is a further object of the invention to provide a device for the above purpose, which is quite simple in its construction, exceedingly strong and durable in practical use, and capable of manufacture at small cost.

35 With the above and other objects in view, my invention consists in the novel features of construction, combination and arrangement of parts to be hereinafter more fully described, claimed and illustrated in the accompanying drawing, in which,

Figure 1 is a side elevation illustrating the application of my improved clamp to the car wheel and rail; Fig. 2 is a vertical sectional view taken on the line 2—2 of Fig. 1; and Fig. 3 is an edge elevation of the clamp.

Referring in detail to the drawing, 5 designates the clamping member proper which is in the form of a single metal casting having a medial, relatively thick portion 6. Upon one end of this clamping member, the angularly disposed lip 7 is formed, and upon the other end thereof, projecting from the same side of the clamping member, a sec-

ond angular lip 8 is formed. It will be noted that this latter lip is of less length than the lip 7. The narrow angularly projecting lip 8 is adapted for engagement beneath the head of the rail on the outer side thereof, while the lip 7 engages over the flange *w* of the car wheel *W*.

The intermediate relatively thick portion 6 of the clamping member is formed with an opening 9 therethrough, said opening being gradually elongated longitudinally of the casting from the outer to the inner face thereof, as clearly shown in Fig. 2 of the drawing. Through this flaring opening, the bolt shank 10 is loosely disposed and has a threaded end portion 11. The other end of this bolt is formed with a hook 12 which is adapted for engagement over the head of the rail on the inner side thereof, as seen in Fig. 2 of the drawing. A clamping nut 13 is engaged upon the threaded end of the bolt, and the outer face of the member 5 which is opposed to the nut is obliquely inclined or beveled, as at 14, to provide the shoulder 15. The nut 13 is provided with a square or rectangular body portion which is adapted to frictionally engage against the inclined face 14.

From the above description, the construction of the device will be clearly understood. Its application in practical use may be readily perceived from an examination of the accompanying drawing. After the lip 8 has been engaged beneath the under side of the rail head and the lip 7 engaged over the flange on the car wheel, the bolt shank 10 is adjusted through the opening 9 in the member 5 so as to clearly engage the hook 12 on the end of said bolt over the inner side of the head. The nut 13 is then threaded inwardly upon the bolt shank into bearing contact against the inclined surface 14 of the casting and said bolt shank drawn through the opening 9 until its hooked end is tightly clamped against the rail head. By providing the flaring opening 9 so that the bolt shank may be oscillated or longitudinally adjusted with respect to the body casting, the device may be more easily and quickly applied to the car wheel and rail and also adjusted to such position with respect thereto as will afford the most secure clamping contact of the several parts with the rail and wheel. After thus securely

clamping the car wheel in place, the journal box may be raised by means of a suitable jack in the ordinary manner.

In the foregoing, I have disclosed the present preferred form and construction of the several parts of my improved clamp, but it is, of course, manifest that the same may be variously modified in these respects and I, therefore, reserve the privilege of adopting all such legitimate changes as may be fairly embodied within the spirit and scope of the invention as claimed.

Having thus fully described my invention, what I desire to claim and secure by Letters Patent is:—

1. A wheel clamp including a body member having angularly disposed lips formed upon its opposite ends for engagement with the outer side of the rail head and the wheel flange respectively, said body member being formed with an opening intermediate of its ends gradually elongated longitudinally of said member from one face thereof to the other, a bolt shank loosely disposed through said opening and provided with a hook on one end for engagement over the inner side of the rail head, and a nut threaded upon the other end of said bolt shank for engagement against the body member to draw the

bolt through said opening and the hook 30 thereon into clamping engagement with the rail head.

2. A car wheel clamp including a body member having angularly disposed lips formed upon its opposite ends for engagement with the outer side of the rail head, and the wheel flange respectively, and having a relatively thick medial portion provided with an opening therethrough gradually elongated longitudinally of said member from one face to the other of the same, the outer face of said body member at the smaller end of said opening being obliquely inclined, a bolt shank loosely disposed through said opening and having a hook 45 formed on one end for engagement over the inner side of the rail head, and a nut threaded upon the other end of said bolt for engagement against the inclined face of said body member to draw the bolt through said 50 opening and the hook thereon into clamping engagement upon the rail head.

In testimony whereof I hereunto affix my signature in the presence of two witnesses.

JAMES T. FIELDS.
